UNITED STATES PATENT OFFICE.

JULIUS BAYER, OF AUGSBURG, GERMANY.

INTERMITTENTLY-OPERATING ABSORPTION REFRIGERATING MACHINE.

Application filed February 4, 1928, Serial No. 251,797, and in Germany February 7, 1927.

This invention has reference to intermittently operating absorption refrigerating machines, particularly those of comparatively restricted output, such as are employed for 5 domestic uses, and adapted to be shipped ready for use and with the absorption liquid contained therein. The invention is intended to facilitate the manipulation by unskilled users and to simplify the construction and the 10 general arrangement of machines of the kind referred to. The invention is particularly applied to machines of this type furnished with separate suction conduits and pressure conduits. In accordance with the previous 15 art such machines have been provided with means adapted to automatically and periodically return the absorption fluid which has been transferred from the boiler into the evaporator, so that in the ordinary and normal 20 course of operation the full calorific efficiency of the machine will always be obtained. With this kind of devices however there is the difficulty that, while they are very well adapted to dispose of the absorption liquid 25 which has been transferred from the boiler into the evaporator during one boiling operation, they fail to operate satisfactorily, whenever it is required to deal with considerable amounts of the absorbing medium, such as 30 will usually overflow into the evaporator during transportation of the machines, and to remove these quantities and to return them to the boiler. In order to attain this object by means of the automatic arrangements referred 35 to a series of boiling operations would become necessary, until the machine would be restored to a state in which it may yield its full efficiency. This inconvenience however results in a very serious interruption of operation 40 with a considerable waste of useful energy, and it is moreover liable to raise suspicion in the mind of the user in regard to the value of the machine.

Now this invention is intended to overcome 45 the difficulties referred to and to produce a satisfactory operation of machines of this kind without the necessity of any particular skilled training or instructing. The machine according to this invention is provided, as 50 hereinbefore mentioned, with separate suction conduits and pressure conduits and moreover with an arrangement otherwise known and adapted to transfer a limited quantity of liquid from the lowest part of the evaporator 55 through the suction pipe into the boiler-ab-

sorber in the beginning of each cooling period. My invention is particularly distinguished by the fact that in the suction pipe a closing valve is disposed which is to be operated at times and which is normally open and by the 60 closing of which the suction conduit is interrupted and the pressure conduit which extends to the bottom of the evaporator is caused to act as a suction conduit, so that by the aspirating action of the absorber the entire liquid contents of the evaporator may be 65 sucked at once into the absorber.

Upon the accompanying drawing I have shown diagrammatically and by way of exemplification the general construction of a 70 refrigerating machine for domestic uses. *a* in the drawing designates the combined boiler-absorber which is provided with the temperature regulating or modifying means, such as electrical heaters *b* and the cooling 75 coil *c*. From the upper part of the boiler absorber *a* the pressure conduit *d* leads to the condenser *e* which is cooled in any suitable manner and which is connected by a pipe *f* to the pocket or sump *g* of the evaporator *h*. Into this pocket *g* of the evaporator the end portion of the suction pipe *i* is likewise disposed, the said suction pipe passing through the evaporator *h* and being provided with a small opening *l* disposed in the interior of a small projecting hood or extension *k*. The suction pipe *i* is provided with a manually operated closing valve *n*. In the normal course of operation this valve *n* is open and the mode of operation of the machine in this stage corresponds to that of the ordinary intermittently operating absorption refrigerating machines. During the process of boiling the vapors of the cooling medium which have been evolved in the boiler *a* will 80 become condensed in the condenser *e* and the condensate formed overflows into the evaporator *h* and fills the evaporator up to the small opening *l* in the suction pipe *i* so that this opening will be covered at the beginning 85 of the absorption period. Upon now interrupting the heating by switching out the heating means *b* and admitting the cooling water to the cooling coil *c* the suctional pressure of the boiler absorber is caused to act 90 through the suction pipe *i* upon the contents of the evaporator *h*, and as a result thereof and in view of the opening *l* being covered up, liquid will be aspirated out of the pocket *g* in which any absorbing medium will ac- 95 100 105 110 115

cumulate which may have flown over into the evaporator, and this action is continued until by the lowering of the level of liquid in the evaporator the opening l is uncovered. The 5 evaporating stage may then commence and the vapors will flow through the opening l and the suction pipe i into the boiler absorber a . In the normal operation of the machine the return of the absorbing medium from 10 the evaporator into the boiler thus automatically obtained will be sufficient. The automatically operating arrangement serving for this purpose may be disposed and constructed in such a manner that at the beginning 15 of each cooling period an amount of liquid is aspirated from the lowest part of the evaporator which corresponds to the quantity of absorbing medium which is the maximum of this liquid likely to be transferred into the 20 evaporator during a boiling operation. When however during transportation, thus for instance by the tilting of the machine, a considerable portion of the contents of the boiler absorber is transferred into the evaporator 25 the automatically operating means are no longer sufficient to release the evaporator in one operation from the absorbing medium. For this purpose the cut-off valve n is closed in the machine described after the termination 30 of the first boiling stage. By this means the suction conduit i is cut out, and the aspirating pressure of the cooled boiler-absorber is acting exclusively upon the deepest portion 35 of the evaporator by way of the condenser e and the conduit $d-f$, the contents of the pocket or deepest part of the evaporator being thereby transferred back into the boiler-absorber in one operation, so as to thereby attain 40 the complete withdrawal of the absorbing agent from the evaporator. After this procedure the valve n is opened again, and the machine is now ready for the ordinary manner of utilization according to which at the beginning of each cooling period the absorbing agent which happens to have escaped 45 into the evaporator, is automatically sucked back into the boiler-absorber, so that the full calorific efficiency will always be obtained.

When the cut-off valve n is closed, it has 50 been found that on account of the absorption and the equalization of pressure occurring in the boiler-absorber the leg of the suction pipe i immersed into the absorber will become filled with liquid up to the cut-off valve n . In 55 order to obviate the possibility of the suction conduit i operating as a siphon between the boiler-absorber a and the evaporator h upon the re-opening of the cut-off valve n , so as to cause the contents of the absorber to 60 flow into the evaporator, the cut-off valve n is arranged above the highest level of the liquid in the boiler-absorber.

In practice modifications and changes of 65 the specific construction herein shown by way of exemplification may be made within the

purview of my invention in accordance with variable conditions of application, except as otherwise stated in the appended claims.

I claim:—

1. In a refrigerating apparatus the combination with a boiler-absorber, an evaporator, communicating means between the top of the boiler-absorber and the bottom of the evaporator and including a condenser, and additional connecting means establishing 75 separate communication between the liquid in the boiler-absorber and the bottom of the evaporator and including a cut-off valve.

2. In a refrigerating apparatus the combination with a boiler-absorber, an evaporator, 80 communicating means between the top of the boiler-absorber and the bottom of the evaporator, condensing means on said communicating means, a conduit independent of said communicating means and leading from the 85 lower part of the boiler-absorber to the bottom of the evaporator, cutting-off means on said conduit above the highest level of said liquid, and heating means and cooling means for the boiler absorber. 90

3. In a refrigerating apparatus in combination, a boiler-absorber, a bulk of liquid in said absorber, an evaporator, a depressed pocket in the bottom of the evaporator, communicating means connecting the top of the 95 boiler-absorber with said pocket, condensing means on said communicating means, a conduit adapted to establish communication of said bulk of liquid with said pocket and apertured in the top part of the evaporator, 100 and a cut-off member in said conduit, and means for varying the temperature of the boiler-absorber.

4. In a refrigerating apparatus in combination, a boiler-absorber, a bulk of vaporizable liquid therein, an evaporator, a pocket in the lower part of the evaporator, communicating means between the top of the boiler absorber and said pocket, and a pipe conduit leading from the position of the liquid in the 105 boiler-absorber to the bottom of the pocket, venting means on said conduit within the top portion of the evaporator and a flow-regulating and flow-closing member in said conduit above the highest liquid-level occurring 115 in the boiler-absorber, and means for varying the temperature of the boiler-absorber. 110

5. In a refrigerating apparatus in combination, a boiler-absorber, a bulk of liquid 120 therein, a closed evaporating tank, communicating and condensing means between the top of the boiler-absorber and the evaporating tank, a pipe conduit leading from the boiler-absorber at the position of the liquid 125 therein to the lower part of said tank, venting means in the top part of said tank and connected to said conduit, flow controlling and interrupting means on said conduit intermediate the boiler-absorber and the tank and

above the highest liquid-level occurring in the boiler-absorber, and temperature-modifying means for said boiler absorber.

6. In a refrigerating apparatus in combination, a boiler-absorber, a bulk of vaporizable liquid therein, a closed evaporating tank, communicating and condensing means between the top of the boiler-absorber and the evaporating tank, a siphon-conduit immersed 10 in the interior of the boiler-absorber and leading to the bottom of the tank and venting means in said siphon-conduit in the top part of the tank, and controlling means in the siphon-conduit.

15. 7. In a refrigerating apparatus in combi-

nation, a boiler-absorber, a closed evaporating tank, a conduit connecting the top of the boiler-absorber and the evaporating tank and including a condenser, a siphon conduit immersed in the liquid of the boiler absorber, 20 and adapted to connect the bottom thereof to the bottom of the evaporator-tank, flow regulating means on the siphon conduit, and temperature modifying means in the boiler-absorber, and venting means for the siphon- 25 conduit in the top portion of the evaporator-tank.

In testimony whereof I affix my signature.

JULIUS BAYER.
